UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,162,508.

Specification of Letters Patent. Patented Nov. 30, 1915.

Original application filed August 26, 1913, Serial No. 786,693. Divided and this application filed May 16, 1914. Serial No. 839,073.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to carriage stops for visible or front-strike typewriting machines and is a division of my pending application, Serial No. 786,693, filed August 26, 1913.

One of the principal objects of the invention 15 is to provide simple and efficient means whereby a plurality of stops or devices may be adjustably supported at the rear of the carriage so as to move therewith and which are adapted to engage a part or parts of the 20 machine not movable with the carriage so that the carriage may be stopped at different points in its backward travel according to the position of said stops.

Another object of the invention is to provide 25 a simple and efficient stop for type-writer carriages which is adapted to be made substantially entirely of sheet metal, as steel, and which is adapted to positively limit the movement of the carriage.

A further object of the invention is to provide 30 simple and efficient means whereby a plurality of stops may be mounted to rock on the carriage in such a way that the carriage after being stopped may be permitted 35 to have a further movement when the stops are released.

With these and other objects in view, the 40 invention will be hereinafter more particularly described with reference to the accompanying drawings, which form a part of this specification, and will then be pointed out in the claims at the end of the description.

In the drawings, Figure 1 is a rear elevation 45 of the upper part of one form of typewriting machine showing the carriage and carriage bed with the invention applied thereto. Fig. 2 is an end elevation of the carriage. Fig. 3 is a plan view of the device or stop with a part of its supporting bar. Fig. 4 is a detail perspective view of 50 one of the stops showing how it is held to

its supporting bar; and Fig. 5 is a detail perspective view showing a slightly different form of device or stop.

The carriage 10 may be of any suitable 55 construction and may be supported in any desired way to travel along a bed 11. A platen 12 is rotatably mounted in the ends 13 of the carriage frame and on the outer end of the platen shaft is a knob or button 14 by which the platen may be rotated, there being the usual or any preferred form of line-spacing mechanism provided to rotate the platen as it is usual in typewriting machines.

A support or bar 15, which may be square 60 in cross-section, extends lengthwise of the carriage and has its ends pivotally held in the ends 13 of the carriage frame. At one end of the supporting bar 15 is a finger lever 16 which is held to said bar and has a key 17 at its forward end to adapt said lever to be depressed to rock the bar 15 on its pivot. The lever 16 has a part 18 extending rearward which is provided with an angular 65 end 19, the said end being adapted normally to rest against the rear edge of one of the carriage frame ends 13. This lever 16 as well as the bar 15 is yieldingly held in its normal position by a spring 20, one end of 70 which spring is held to the bar 15 and the other end to the carriage frame, said spring tending normally to force the end 19 of the lever 16 into engagement with the carriage 75 frame.

The supporting bar 15 has a plurality of 80 stops or devices 21, 22 and 23 mounted thereon. These stops are exactly the same in construction except that the stop 22 is somewhat shorter than the other stops, and while only three stops are shown, there may be any desired number or only one may be employed if preferred. These stops or devices may be variously constructed. As 85 shown, each stop comprises two members 24 and 25. The locking member 24 is provided with a head 26 and the guiding member 25 is provided with a head 27. These members are made of flat sheet metal, as steel, formed by dies or otherwise and the heads 26 and 27 90 are each substantially U-shaped in plan, the head of one member fitting within the other 95 100

member in such a way as to permit relative movement. The head 27 may be called the guiding head for the device and 26 the locking head. The bar 15 has a plurality of 5 vertically extending slots 28 which are spaced apart, and adapted to engage said slots is a dog or tooth 29 of the head 26. The guiding head 27 is provided with openings through the side plates or walls 30 of 10 substantially the same size and shape as the bar 15 in order that the entire device may be properly guided along the bar 15, while the head 25 has an opening longer than the bar 15 on the wall or side 31 15 only. The side or wall 32 of the head 26 is relatively shorter than the side 31 and permits said head 26 to span the head 27 and be guided properly thereby. The head 26 has a pendent part or arm 33 which is 20 secured to the pendent part or arm 34 by a screw 35 or otherwise. A flat spring 36 is interposed between the arms or parts 33 and 34 and extends upward between the heads 26 and 27 and normally forces one of the 25 heads along the other and normally causes the dog or tooth 29 to engage one of the slots of the bar 15 so as to be held to the bar 15 in one of the adjustments of said stop. The head 26 is roughened, at 37, to 30 provide a finger surface so that by pressing with the finger on the head 26, the tooth 29 may be disengaged from one of the slots 28 and the entire device moved along the bar 15, and on releasing the head 26 of any 35 pressure by the finger, the device will be locked to the bar in any desired position.

A bracket 38 may be secured by screws 39 or otherwise to the carriage bed 11 and may be provided with a projecting engaging 40 portion or stop 40 arranged in the path of the pendent arms of any one of the stops 21, 22 and 23. The carriage may be moved along the bed 11 by the action of the letter spacing and tension means in the usual way 45 which will cause one of the stops, as the stop 21 for example, to engage the projecting part 40 of the bracket and hold the carriage against further movement. If the arm or lever 16 is depressed to rock the bar 15 on 50 its pivot, the pendent part of the stop 21 may be moved out of the path of the part 40 so that the carriage may have further movement. On the return movement of the carriage, the pendent arm of the stop 22 55 will engage the part 40 and lock the carriage against further movement unless released by rocking the bar 15 when the carriage can be moved farther backward and until the stop 23 engages said part 40. 60 These stops may be of any desired number and may be located at any desired part of the machine to adapt the stops for tabulating or other purposes, and said stops may be made to engage a part of the bracket 38 65 or any other desired part of the machine.

In Fig. 5, the construction is exactly the same as either of the stops described except that the spring 36 is dispensed with. In such case, the member 33 may be of spring metal to permit relative movement of the 70 members 24 and 25. A spiral spring instead of a flat spring may be used and either kind of spring may be employed with a spring part 33 if desired.

From the foregoing, it will be evident 75 that a simple and efficient stop is provided; that a simple and efficient mounting for one or more stops is provided whereby the said stops may be caused to hold the carriage against movement at any desired point in 80 its travel; and that said stop is simple in construction and may be made by dies from sheet metal or otherwise formed.

Having thus described my invention, I claim as new and desire to secure by Letters 85 Patent:—

1. The combination of a support, a carriage movable along said support, a member movable with the carriage, and a device forming a stop for the carriage and having 90 two members each provided with a substantially U-shaped head, one movable on the other and one of which is adapted to engage the member for adjustment thereon, said heads having integral pendent portions attached to each other to adapt one head to be moved relatively to the other.

2. The combination of a support, a carriage movable along said support, a member, and a sheet metal device forming a stop 10 for the carriage and having two members each provided with a substantially U-shaped plate-head, one movable on the other and one of which is adapted to engage the member for adjustment thereon, said heads having pendent portions attached to each other to adapt one head to be moved relatively to the other.

3. The combination of a support, a carriage movable along said support, a normally fixed bracket, a bar-like member movable with the carriage, and a device forming a stop for the carriage adapted to engage said bracket and having two members each provided with a substantially U-shaped 110 head, one movable on the other and one of which is adapted to engage the bar-like member for adjustment thereon, said heads having integral pendent portions attached to each other at their lower ends to adapt 120 one head to be moved relatively to the other.

4. The combination of a carriage, a support on the carriage, and a device adjustable on said support and comprising two relatively movable members formed of sheet 125 metal and provided with substantially U-shaped unattached heads one spanning and slidable on the other and serving to limit the movement of the carriage.

5. The combination of a carriage, a tilt- 130

able bar on the carriage, and a device adjustable on said bar and comprising two relatively movable members formed of sheet metal and provided with unattached heads 5 one fitting about and slidable on the other and serving to limit the movement of the carriage.

6. The combination of a carriage, a slotted bar on the carriage, and a device having a 10 tooth to engage the slots of said bar and adjustable thereon and comprising two relatively movable members and provided with substantially U-shaped unattached heads one fitting about and slidable on the other and 15 serving to limit the movement of the carriage.

7. In a typewriting machine, a stop for 20 limiting the movement of the carriage comprising two relatively movable members 25 having overlapping plate-like heads fitting about and entirely free of each other.

8. The combination of a carriage, a support on said carriage, and a device for limiting the movement of the carriage and adjustable on said support and comprising two relatively movable members having overlapping plate-like heads each provided with spaced side walls, the walls of one head bearing against and fitting within the walls 30 of the other head.

9. The combination of a carriage, a slotted support on said carriage, and a device comprising two relatively movable and overlapping plate-like and substantially U-shaped members fitting about each other, means for adjustably holding the members to said support, and yielding means tending normally to separate said members.

10. In a typewriting machine, a stop comprising two relatively movable and overlapping plate-like and substantially U-shaped members fitting about each other, and yielding means tending normally to separate said members.

45 11. In a typewriting machine, a slotted support, and a device comprising two relatively movable and overlapping plate-like and substantially U-shaped members fitting about each other, means for adjustably holding the members to said support, and yielding means tending normally to separate said members.

12. The combination of a carriage, a support having slots, and a plurality of devices 55 each serving to limit the movement of the carriage and comprising a guiding member formed with a stem portion and a plate-like and U-shaped head having spaced parts provided with openings to be guided on the support, and an engaging member having a 60 U-shaped head and adapted to engage the slots on the support to adjust the device along said support and provided with a yielding pendent portion permanently attached to the stem portion of the guiding member.

member to permit the head of the engaging member to be moved relatively to the guiding member.

13. In a typewriting machine, a slotted support, and a device serving to limit the 70 movement of the carriage and comprising a guiding member formed with a stem portion and a plate-like head having spaced parts provided with openings to be guided on the support, and an engaging member having a head and adapted to engage the slots on the support to adjust the device along said support and provided with a pendent portion permanently attached to the stem portion of the guiding member to permit the head of the engaging member to be moved relatively to the guiding member.

14. The combination of a carriage, a support on said carriage having slots, and a device serving to limit the movement of the 80 carriage and comprising a guiding member formed with a stem portion and a plate-like head having spaced parts provided with openings to be guided on the support, and an engaging member having a head provided with a tooth adapted to engage the slots on the support to adjust the device along said support and provided with a yielding pendent portion permanently attached to the stem portion of the guiding 90 member to permit the head of the engaging member to be moved relatively to the guiding member.

15. The combination of a carriage, a support on the carriage, and a device for limiting the movement of the carriage and comprising a member having spaced plate-like walls adapted to engage the support, and a guiding member fitting into the engaging member between its walls and having slot- 100 ted spaced plate-like walls adapted to fit over the support.

16. The combination of a carriage, a support, and a device for limiting the movement of the carriage and comprising a member 110 adapted to engage the support, and a guiding member fitting into the engaging member and having slotted spaced walls through which the support passes.

17. The combination with a carriage, of a bar extending lengthwise of the carriage and having a plurality of slots, a plurality of devices held upon said bar for limiting the movement of the carriage, each of said devices comprising two relatively movable 120 members, one of said members having a yielding part and a part to span the bar and provided with means to engage the slots of the bar and hold the device against movement until released, and the other having a pendent portion to which the yielding part of the slot engaging member is attached.

18. The combination with a carriage, of a bar having a plurality of slots, means for tilting said bar, a stop, a plurality of de- 130

5 vices held upon said bar for limiting the movement of the carriage by engagement with said stop, each of said devices comprising two relatively movable members, one of said members having a yielding part and a part to span the bar and provided with means to engage the slots of the bar and hold the device against movement until released, and the other having a pendent

portion to which the yielding part of the 10 slot engaging member is attached.

This specification signed and witnessed this 12th day of May A. D. 1914.

OTTO PETERMANN.
